UNITED STATES PATENT OFFICE.

CHARLES M. ROGERS, OF MAYO, SOUTH CAROLINA.

SEPARATOR-RETAINER FOR SPINNING-FRAMES.

1,370,154.

Specification of Letters Patent.

Patented Mar. 1, 1921.

Application filed June 4, 1920. Serial No. 386,424.

To all whom it may concern:

Be it known that I, CHARLES M. ROGERS, a citizen of the United States, residing at Mayo, county of Spartanburg and State of 5 South Carolina, have invented certain new and useful improvements in Separator- 60 Retainers for Spinning-Frames; and I do hereby declare the following to be a full, clear, and exact description of the invention, 10 such as will enable others skilled in the art to which it appertains to make and use the same.

The present invention relates to separators for spinning frames, and aims to 15 provide simple yet efficient means for retaining the separator rods in the slots of the supporting arms, thereby preventing the rods from becoming unhooked or jumping out of their slots when the frame runs full, 20 and the separator is turned back to permit the doffing of the bobbins from the spindles, which not infrequently occurs with the separator construction now in general use.

It is the object of the invention to provide 25 a retainer adapted to be applied to an ordinary separator construction, for retaining the separator rods in place against accidental unhooking or disconnection from the supporting arms or hooks, and permitting 30 the separator to be operated as usual.

With the foregoing and other objects in view, which will be apparent as the description proceeds, the invention resides in the construction and arrangement of parts hereinafter described and claimed, it being understood that changes can be made within the scope of what is claimed, without departing from the spirit of the invention.

The invention is illustrated in the accompanying drawing, wherein:—

Figure 1 is a fragmentary elevation of the separator construction showing the retainer applied, and the separator in normal operative position.

Fig. 2 is a fragmentary elevation showing the separator swung back as when doffing the bobbins from the spindles.

Fig. 3 is a fragmentary front view of the device.

The separator construction illustrated is of a well known type. 6 indicates the spindle rail carrying the bobbins 8, and 7 indicates the ring rail which is movable upwardly and downwardly as usual. The separators 9, which are disposed between the

bobbins to prevent tangling of the yarn, are carried as usual for rocking movement to and from operative position by means of a pair of parallel supporting rods 10 and 11. Each separator 9 has a foot 12 bearing 60 against said rod, and a clamping block 13 is disposed opposite to said foot and they are connected by a bolt 14 or other securing means serving to clamp the separator to the rods. 65

A lever or bracket 16 has one end mounted on a fulcrum shaft or stud 15, and is provided at its other end with an arm 17 extending upwardly at an angle and provided with a rearwardly opening slot 18 receiving the rod 11 and in which said rod is seated. The arm 17 with its slot 18 forms a hook removably receiving the rod 11, and the rod 10 is movable around the end of the arm 17 to permit of the swinging movement 75 of the separators, to and from operative position.

An angular auxiliary lever 19 has its elbow fulcrumed, by means of a pin 20, to the lever 16 at the lower end of the arm or hook 70 17, and has an upwardly projecting arm 21 to bear against the block 13 (or the rods 10 and 11) and said lever 19 has a rearwardly extending arm 22 having a pin and slot connection 23 with one arm of a lever 24 fulcrumed between its ends on the shaft or stud 15. The other arm of the lever 24 carries an adjustable weight 25, which normally has a tendency to swing the lever 19 for pressing the arm 21 against the block 13, and 90 holding the separators in operative position, as seen in Fig. 1. When the separators are swung upwardly and rearwardly, as seen in Fig. 2, the block 13 will swing the arm 21 rearwardly, thereby swinging the arm 22 95 downwardly and raising the weight 25. This enables the separators to be turned back out of the way (or down as shown in dot and dash lines in Fig. 2) during the doffing of the bobbins from the spindles, and 100 when the new bobbins are applied, the separators can be readily returned to operative position and the pressure of the arm 21 against the block 13 will assist in returning the separators and causing them to assume 105 the proper position.

The foregoing structure is well known and in common use, and has the objection, that the separator rod 11 will not infrequently become unhooked from the arm 17 110

by moving out of the slot 18 when the separators are swung to the position shown in Fig. 2.

In carrying out the invention, a retainer bar or strip 26 is used, being provided with an aperture 27 near its lower end to engage over the pivot pin 20 of the lever 19, and said bar is retained on said pin by means of the cotter pin 28 or the like. The bar 26 is provided near its upper end with an oblique slot 29 to receive the rod 11, and extending in a direction opposite to the slot 18 thereby forming a hook to engage the rod 11 from between the two separator rods 10 and 11. The bar 26 in thus engaging over the rod 11 and in being anchored to the pin 20, will retain said rod 11 in the slot 18, thereby preventing accidental unhooking or disconnection of the separator rods. The bar 26 is readily applied by engaging the hook upwardly or outwardly between the rods 10 and 11 over the rod 11, and the lower end of the bar is then engaged over the pin 20 and held in place by the cotter pin 28. By removing the cotter pin 28, the bar 26 can be slid off of the pivot pin 20 and then removed from the rod 11.

Having thus described the invention what is claimed as new is:—

30 1. In a separator construction, the combination of a supporting arm having a slot, a separator, means supporting said separator including a rod seated in said slot for the movement of the separator to different positions, a lever controlling the separator, a pivot pin connecting said lever and arm for the swinging movement of said lever, and a retainer bar having a hook to engage said rod and an aperture to engage 35 said pin whereby to hold said rod in said slot.

2. In a separator construction, the combination of a supporting arm having a slot, a pin projecting from the arm, a separator, parallel rods supporting said separator, one of the rods being seated in said slot for the movement of the separator to and from operative position, and a retainer bar having a hook to engage said rod and an aperture to engage over said pin so as to hold said 45 rod in the slot.

3. In a separator construction, the combination of a supporting arm having a slot, a separator, parallel rods supporting said separator, one of the rods being seated 55 in said slot for the movement of the separator to and from operative position, a lever for holding the separator in operative position, a pivot pin connecting said lever to the arm, and a retainer bar engaging said 60 pin and provided near one end with a slot receiving said rod and forming a hook engaging over said rod between the two rods, the slot of said bar opening in a direction opposite to the first named slot.

4. In a separator construction, the combination of a supporting arm having a slot, a separator, means supporting said separator including a rod seated in said slot for the movement of the separator to different positions, a retainer member having a hook to engage over said rod, and means for the attachment of said bar to said arm so as to prevent said rod from moving out of said slot.

In testimony whereof I have signed my name to this specification in the presence of two subscribing witnesses.

CHARLIE M. ROGERS.
